(57) **CLAIM**

The ornamental design for an optical protection device as shown and described.

DESCRIPTION

FIG. 1 is a front perspective view of an optical protection device in accordance with the present invention;

FIG. 2 is a rear perspective view of the optical protection device shown in FIG. 1;

FIG. 3 is a front view of the optical protection device shown in FIG. 1;

FIG. 4 is a rear view of the optical protection device shown in FIG. 1;

FIG. 5 is a right side view of the optical protection device shown in FIG. 1;

FIG. 6 is a left side view of the optical protection device shown in FIG. 1;

FIG. 7 is a top view of the optical protection device shown in FIG. 1; and,

FIG. 8 is a bottom view of the optical protection device shown in FIG. 1.

The features shown in broken lines in the various Figures are for illustrating the environmental structure and form no part of the claimed design.
